(57) **CLAIM**

The ornamental design for a totem toy set, as shown and described.

DESCRIPTION

FIG. 1 is a perspective view of a totem toy set;
FIG. 2 is a perspective view of a first piece thereof;
FIG. 3 is a front elevation view thereof;
FIG. 4 is a rear elevation view thereof;
FIG. 5 is a right side elevation view thereof;
FIG. 6 is a left side elevation view thereof;
FIG. 7 is a bottom plan view thereof;
FIG. 8 is a top plan view thereof;
FIG. 9 is a perspective view of a second piece of the totem toy set;
FIG. 10 is a front elevation view thereof;
FIG. 11 is a rear elevation view thereof;
FIG. 12 is a right side elevation view thereof;
FIG. 13 is a left side elevation view thereof;
FIG. 14 is a bottom plan view thereof;
FIG. 15 is a top plan view thereof;
FIG. 16 is a perspective view of a third piece of the totem toy set;
FIG. 17 is a front elevation view thereof;
FIG. 18 is a rear elevation view thereof;
FIG. 19 is a right side elevation view thereof;
FIG. 20 is a left side elevation view thereof;
FIG. 21 is a bottom plan view thereof;
FIG. 22 is a top plan view thereof;
FIG. 23 is a perspective view of a fourth piece of the totem toy set;
FIG. 24 is a front elevation view thereof;
FIG. 25 is a rear elevation view thereof;
FIG. 26 is a right side elevation view thereof;
FIG. 27 is a left side elevation view thereof;
FIG. 28 is a bottom plan view thereof;
FIG. 29 is a top plan view thereof;
FIG. 30 is a perspective view of a fifth piece of the totem toy set;
FIG. 31 is a front elevation view thereof;
FIG. 32 is a rear elevation view thereof;
FIG. 33 is a right side elevation view thereof;

(Continued)

FIG. 34 is a left side elevation view thereof;
 FIG. 35 is a bottom plan view thereof;
 FIG. 36 is a top plan view thereof;
 FIG. 37 is a perspective view of a sixth piece of the totem toy set;
 FIG. 38 is a front elevation view thereof;
 FIG. 39 is a rear elevation view thereof;
 FIG. 40 is a right side elevation view thereof;
 FIG. 41 is a left side elevation view thereof;
 FIG. 42 is a bottom plan view thereof;
 FIG. 43 is a top plan view thereof;
 FIG. 44 is a perspective view of a seventh piece of the totem toy set;
 FIG. 45 is a front elevation view thereof;
 FIG. 46 is a rear elevation view thereof;
 FIG. 47 is a right side elevation view thereof;
 FIG. 48 is a left side elevation view thereof;
 FIG. 49 is a bottom plan view thereof;
 FIG. 50 is a top plan view thereof;
 FIG. 51 is a perspective view of an eighth piece of the totem toy set;
 FIG. 52 is a front elevation view thereof;
 FIG. 53 is a rear elevation view thereof;
 FIG. 54 is a right side elevation view thereof;
 FIG. 55 is a left side elevation view thereof;
 FIG. 56 is a bottom plan view thereof; and,
 FIG. 57 is a top plan view thereof.
 The broken lines are for the purpose of illustrating portions of the article that form no part of the claimed design.
